UNITED STATES PATENT OFFICE.

ARTHUR I. ENGLISH, OF NEWTON CENTER, MASSACHUSETTS, ASSIGNOR OF TWO-THIRDS
TO BENJAMIN A. HOWES, OF NEW YORK, N. Y.

CONCRETE-MOLD.

1,271,874.

Specification of Letters Patent.

Patented July 9, 1918.

Application filed January 2, 1908, Serial No. 408,928. Renewed May 14, 1918. Serial No. 234,534.

To all whom it may concern:

Be it known that I, ARTHUR I. ENGLISH, a citizen of the United States, residing at Newton Center, in the county of Middlesex and State of Massachusetts, have invented certain new and useful Improvements in Concrete-Molds, of which the following is a specification.

This invention relates to molds or means whereby plastic material such as concrete is retained in proper form while being cast. While the invention is particularly adapted for use in connection with the construction of concrete buildings, it may have application for other purposes and in connection with other moldable materials than concrete.

Generally speaking the object of the invention is to reduce the cost of construction of concrete and other structures to which the invention is applicable, both as regards the material of which the molds are constructed and the labor required.

Specific objects of the invention are,

First,—the provision of a skeleton frame which conforms to the main lines of the building to be constructed, this frame being set up plumb and true so that the sections forming the retaining walls for the plastic material may be laid up against the frame, thus doing away with the necessity of plumbing and alining each separate unit of the walls as it is placed in position. Also the retaining wall for the plastic material forming a floor of the building may be supported upon this frame and the floor construction can be carried on at the same time that the side walls of the building are being erected.

Second,—to permit the use of random lumber, planed or unplanned and without previous preparation.

Third,—the provision of improved means for securing the sections forming the retaining wall in proper position but permitting the sections to be separately removed whereby after the casting of the lower portions of the plastic material the sections of those portions of the wall may be removed therefrom and reused higher up.

Fourth,—the provision of driven fastenings for securing the sections forming the retaining walls whereby the said sections after having been adjusted to position may be securely and accurately fixed in their adjusted positions by driving home the fasten-

ings, no nuts or screw threads being necessary.

Other and ancillary objects of the invention will appear hereinafter.

The invention can be best explained in connection with the accompanying drawings, which illustrate it, and of which,

Figure 1 is a side elevation of a wall mold for the construction of a concrete building, the concrete walls being partially constructed, some of the parts of the mold being broken away;

Fig. 2 is a combination, plan and sectional view taken on the line 2--2 of Fig. 1;

Figs. 3, 4, 5, 6, 7 and 8 are views of different forms of means for securing and supporting various portions of the mold as will hereinafter appear;

Fig. 9 is a horizontal section through a portion of the mold for a concrete building showing a modified construction of corner mold, this view being taken on the line 9—9 of Fig. 10;

Fig. 10 is a side elevation, looking in the direction of the arrow, of the structure shown in Fig. 9;

Fig. 11 is a view similar to Fig. 9 showing still another construction of mold for a corner; and,

Fig. 12 is a vertical transverse section of a side wall of a building showing the manner of removing a section of a retaining wall, a fragment of the wall being shown.

Referring to the drawings, a skeleton frame for the first story of the building, and which conforms to the main lines of the building, comprises uprights which may consist of the corner posts 1, 2 and 3, etc., one at each corner of the building to be constructed which, as will be seen from Fig. 2, is in this case rectangular in plan. Other uprights for this first story may be pier boxes 4, 5 and 6. The uprights are secured together by means of horizontal beams 7, 8, 9, etc., which extend between the uprights and serve to bind the whole into a stable frame. In addition to these beams girder boxes as 10 may extend from one side of the frame to the other and other beams may be suitably placed to support the floor, or for other purposes as required. Of course where girder or pier boxes are not necessary, this being determined by the judgment of the architect, one or both may be omitted. The girder boxes open at their

ends, as shown, into the pier boxes, so that in the concrete structure the piers are directly beneath the girders. The frame will usually be formed of wood but may be constructed of any other suitable material.

Against the uprights of the frame are laid the sections or plates which constitute the inside retaining walls for the concrete forming the side walls of the building. The sections are usually wooden planks of the common rectangular cross section and no special preparation of them is required such as providing holes for dowel pins, or tongues, or grooves or other special formation for securing or alining the sections. These planks are laid up edge to edge against the skeleton frame; thus one retaining wall is formed of the planks 11, another of the planks 12, another of the planks 13, &c. The uprights of the skeleton frame furnish guides for the retaining wall sections and, the frame having been erected plumb and true, this guiding of the planks by the frame will result in the formation of true concrete walls without the necessity of plumbing and truing the different sections of the retaining walls as they are laid up.

In the structure shown, the planks forming the retaining walls are laid against the cleats as 14 and 15 which are secured to the outside of the pier boxes and similar cleats 14' and 15' secured to the posts. These cleats are virtually parts of the boxes and posts to which they are respectively secured and are so located as to bring the planks substantially flush with the pier box edges and the faces of the posts respectively, as shown. In order that the planks may be prevented from bulging under the pressure of the concrete or from other causes, buttons 16 are secured to the outer sides of the planks that is, on the sides opposite those against which the concrete bears, and these buttons project beyond the upper edges of the planks so as to overlap the outer sides of the lower edges of the planks above.

In order to prevent the planks from bulging out of alinement horizontally, cleats as 17 are employed where the ends of two planks abut, the cleats being secured to the outside of one of the two abutting planks and extending beyond the edge thereof so as to overlap the end of the other abutting plank.

At a suitable distance from the frame just described, are arranged uprights as 18 and 19, which in this case are corner posts and against which are laid the planks or sections forming the outside retaining walls which are opposed to the inside retaining walls for the concrete, the latter walls being laid up against the skeleton frame as before described. Buttress boxes as 19' and 20 may be provided where necessary or desirable, and may to a certain extent act as

guides for the sections forming the outer walls. Cleats as 21 and 22 may be secured to the outside of the buttress boxes, these cleats being similar to the cleats as 14 and 15 upon the pier boxes and 14' and 15' upon the corner posts. The planks forming the retaining walls bear against the cleats 21 and 22 in a similar manner to that in which the planks bear against the cleats 14 and 15, 14' and 15'.

At each of the corner posts, as 19, the planks as 23 forming one of the retaining walls overlap the post while the planks 24, forming a retaining wall extending at an angle to the last, abut against the side of the post and are held substantially flush with the inside surface thereof by means of a cleat as 25.

Each of the outside uprights may be secured in position by a means 26 comprising a rod and driven fastenings at the ends thereof, the fastenings at one end being driven into the end of one of the outside uprights while the fastening at the other end of the rod is driven into the end of an inside upright.

A means 27, similar to the means 26, may be employed for spacing and securing the sections of the opposing retaining walls in proper position, the driven fastenings at the ends of the rods in each of the means 27 being driven into the edges of oppositely located planks or sections in the outside and inside retaining walls. The means 26 and 27 will be referred to more specifically hereinafter.

Rods as 28, having driven fastenings at their ends, may be employed for securing the planks of the retaining walls to the pier boxes and similar bars as 29 may also be employed for securing the planks to the buttress boxes.

Whenever it is desired to form an opening, such as a door or window, in the concrete wall, a frame 30 may be placed between the inner and outer retaining walls, the continuity of these walls not being interrupted, they extending across the opening. The frame however will serve to keep the concrete out of the opening which will appear in the concrete wall when the retaining walls are removed.

To the sides of the girder boxes, which in this case serve as horizontal beams in the frame work, cleats as 31 and 32 are secured and against these cleats are laid the concrete floor retaining planks 33 which planks are supported by the horizontal beams of the skeleton frame which in turn are supported by the uprights of that frame.

Blocks as 34 are placed beneath the lowest planks of the retaining walls for a purpose as will hereinafter appear.

To describe more specifically the means hereinbefore referred to by the reference

75

numerals 26 and 27, reference is made to Fig. 8 which shows an enlarged view of such means. Fig. 8 shows a metal rod having its ends 35 and 36 bent at angles to the main portion of the rod and upon the same side of the axis thereof and lying in the same plane. These ends may be sharpened as shown and are driven after the manner of a nail, which form of fastening is known 10 in mechanics as a driven fastening.

The securing means referred to may take the form as shown in Fig. 8 or it may have a kink such as the loop 37 in Fig. 6 or the kink may be simply a bend 38 as shown in 15 Fig. 7, this irregularity or kink being for a purpose as will be hereinafter referred to. Where it is desired to secure the ends of the rod to surfaces lying in different planes, the driven fastenings at the ends of the rod 20 may be made to lie in different planes as shown in Fig. 4 in which the fastenings 39 and 40 lie in planes at 90° with each other, instead of lying in the same plane as do the fastenings 35 and 36 in Fig. 8. The securing means 28 and 29 (see Fig. 2) are like that shown in Fig. 4. Of course the fastenings may lie in planes differing from each other by any desired angle. In Fig. 5 the bar is shown as having driven fastenings at 25 its ends extending on both sides of its axis. This is for use where it is desired that the ends of the bar shall be secured to the sections upon both sides of it.

The manner of use of the improved molds hereinbefore described may now be set forth. The skeleton frame consisting of the uprights and horizontal beams, within which may be included the pier or girder boxes where necessary or desirable, as before described, is first placed in position, plumb and true. To the uprights and horizontal beams or girder boxes are secured the cleats, which are virtually a part of these uprights and beams, where necessary to provide bearings for the planks of the retaining walls. The uprights for the outer retaining walls are then secured in position, cleats being secured to them to provide the necessary bearing surfaces for the planks of the retaining walls as before described. The lowest planks are then placed in position against the skeleton frame. The lowest planks of the opposing retaining wall are 50 then placed in position against the outer upright and the planks are then secured in position and spaced apart by means 27 (see Fig. 8), the bent ends of the rods being driven into the edges of planks in the opposing walls. These bottom planks rest upon blocks 34 as before referred to. The bottom course of planks having been secured in position as described, the next course of planks 55 is laid thereon and are positioned and secured in the same manner as the bottom

course of planks. In this manner the retaining walls can be carried up to any height desired. Usually this will be to a height approximately equal to that of the concrete wall which is to be cast in one day. The concrete cast on one day will usually be sufficiently set by the next so that it will maintain its form when the retaining walls are removed. With varying conditions, however, different amounts of the retaining walls 75 may be laid up at one time and may be taken down as the circumstances may dictate. This will be governed largely by the character of the plastic material employed, the rapidity with which the work is carried on and other causes which will depend upon the circumstances surrounding the particular building under construction and to which the molds herein described will be readily adapted by those skilled in the art. 80

The retaining walls having been laid up to the desired height, the concrete, herein indicated by the reference numeral 40', is placed within the retaining walls where it surrounds the securing and spacing means 27. It will be noted that the pier boxes open upon one side into the space between the retaining walls so that the piers and walls are cast together to form an integral structure. Similarly the buttress boxes open on one side into the space between the retaining walls and are cast integral with the walls of the concrete structure. 85

The retaining walls never being at a much greater height than the concrete between them, and this height can be made any that is desired, it is easy to tamp and spade the concrete, reinforcement can be placed where wanted as the work progresses and it is unnecessary to cast the concrete from any great height so that the likelihood of separation of the ingredients and consequent honeycombed places in the walls are avoided. 100

The means 27 are preferably driven flush with the planks, as shown in Figs. 1, 10 and 12, so that no space is formed between two adjacent sections of a retaining wall through which the concrete could exude. 105

The concrete having been filled in between the retaining walls to the desired height, as for instance, to the middle of the top planks, the bottom planks can be removed, and placed upon the top course of the planks. This procedure progresses until the interior retaining walls reach the underside of the second floor line, or beam, or girder box and if, at the last, a space is left into which the usual planks will not fit, boards may be cut to fill this space. The outside retaining wall may be carried up indefinitely without break by piling the planks one above the other as described. 115

As shown in Figs. 1 and 12, the means 27 extend from between adjacent sections of 120 125

one retaining wall, through the space for the concrete and in between adjacent sections of the other wall. Each of the securing means 27 is fastened to the section upon but one 5 side of it by having its ends driven into the tops of the planks adjacent to it. This holds the top from moving sidewise. The section upon the other side of the securing means 27 are unsecured against this sidewise movement and may be moved outwardly. The 10 cleats on the uprights are made in sections, where necessary, so that the sections may be removed to permit the removal of the planks. The concrete having been cast in the mold, 15 the necessary cleat section or sections may be removed, when the bottom plank of the retaining wall on each side may be pulled outwardly to clear the blocks 34 and may then be moved downwardly to disengage from the 20 driven fastenings. The blocks 34 are preferably from one half to three fourths of an inch in height and serve to prevent the bottom plank from being jammed against the floor by reason of swelling, or from other 25 causes, and provide a clearance which facilitates access to the bottom of the plank so that it may be engaged to move it outwardly. After the removal of a plank, those above it 30 are supported by the ends of the anchors which project beneath them from the concrete and may be removed in a similar way. The manner of thus removing a plank is clearly indicated in Fig. 12. It is to be observed that the cleats 17 are beveled at their 35 ends to prevent binding between a plank which is being removed and the one above it.

The planks as 33 for the floor retaining walls are laid upon the horizontal beams or girder boxes, as before described, and the 40 concrete 41 forming the floor for the second story is laid thereon and beveled off to the desired thickness. It is not necessary that a complete retaining wall be laid from side to side of the frame but, in a manner analogous 45 to that of the laying up of the side retaining walls, the floor wall may, beginning at one side, be laid toward the other side to any extent desired and, the concrete having been cast upon the portion of the wall thus laid, 50 the plank at one end under the concrete may be removed and placed at the other side of the planks. This procedure can be carried out until the wall has progressed from one side of the frame to the other and the concrete floor completed. The cleats as 31 upon 55 which the floor rests are divided into sections where necessary, similarly to the cleat 25, so that by removing the different sections the different planks may be removed. The 60 concrete forming the floor is leveled off to the desired thickness and takes into the girder boxes, the upper sides of which are open (see Figs. 1 and 2) so that the concrete girders are cast integral with the floor. The 65 concrete forming the side walls joins that

forming the floor as shown clearly in Fig. 1 so that the side walls and floors form an integral structure.

It is to be observed that by the improved mold employed, it is not necessary to wait 70 until the concrete side walls have reached the second story before the retaining wall for the floor of that story can be laid. The retaining walls for the floor may be laid upon the skeleton frame without regard to the 75 condition of the side walls and the reinforcement placed in position thereon. This simultaneous laying of the mold for the side walls and floors greatly expedites the work. By the time the floors are reached with the 80 concrete they are in condition for the concrete to be cast thereon and this casting of the concrete for the floor may even be begun before the side walls have reached them.

To continue the structure higher than one 85 story, after the floor of the second story has been laid a skeleton frame similar to that used for the first story is erected on the floor of the second story and the operations described repeated. The outside corner posts 90 of the second story may be continuous with those of the first story or the sections corresponding to the different stories may be mounted one on the end of another as is shown clearly in the case of the first and second story outside corner posts 19 and 59. The frame and uprights for the second story having been erected as described, planks are laid up against them to form the retaining walls in precisely the same manner as the 95 retaining walls of the first story were placed. The bottom planks of the inside retaining walls of the second story are supported by blocks 34' which rest upon the concrete floor of that story, these blocks being analogous 100 to the blocks 34. As before stated, the outside retaining walls may be laid up continuously with those of the first story. The manipulation of the retaining wall planks is precisely the same in the case of the second 105 story as in that of the first. The retaining wall for the third story floor is supported by the second story frame in a manner precisely analogous to that in which the retaining wall planks for the second story floor are supported by the first story frame. The concrete structure having been carried up to the third story, a third story frame may be erected thereon and another story added to the concrete structure. This process can be 110 carried on for an indefinite period the building rising to any height or number of stories 115 desired.

It will have been observed that as the concrete walls are formed, the anchors for 120 the retaining wall sections will become embedded in the concrete and, upon the removal of the planks, their ends will project from the concrete as clearly shown in Figs. 1 and 12. These ends are to be cut off, the 130

remainders of the anchors remaining in the concrete. Of course, where desired, these projecting ends of the anchors, for the purpose of effecting attachments to the walls 5 or for other purposes, may be left on. In cutting off the ends of the anchors or in other ways, the form of anchor shown in Fig. 8 might become loosened in the wall sufficiently to push off plastering which may 10 have been applied to one side of the wall before the end of the anchor upon the other side of the wall is cut off, or seepage of water or the penetration of moisture might be permitted. To avoid these disadvantages, 15 the forms of anchors shown in Figs. 6 and 7 are provided, the kink 37 or 38, as the case may be, serving to firmly secure the anchor within the wall.

The form of anchor shown in Fig. 5 may 20 be economically used where it is desired to lay up the entire retaining walls before removing the bottom planks. In such cases the walls should be allowed to harden so that in bending the anchors and in taking down 25 the planks the walls will not be chipped. Where this form of anchor is used the buttons 16 are unnecessary.

The modified corner centering shown in 30 Figs. 9 and 10 is intended for use in connection with work which is finely finished and in which the corners of the concrete structure must be absolutely true. In this modified construction the inside corner upright is formed of a plurality of vertically 35 extending planks 60 and 61 which are braced and secured by the angular brackets 62. The outer corner upright is formed of vertically extending planks 63, 64, 65 and 66 which are bound together and to the inside 40 uprights by means of the battens 67 and 68, which are secured together at the corner by an angle iron 69 which is secured by lag screws to the battens, and the bolts 70 and 71 with their surrounding sleeves 72 and 73. 45 One of these bolts with its sleeve is shown enlarged in Fig. 3. This bolt has an elongated head 74 at one end and a screw thread 75 at the other end with which engages a nut 76. These bolts pass through 50 the vertical planks of the inner and outer uprights and also through the battens as shown. The bolts are so located that the elongated heads are in proximity to the brackets 62 so that the bolts are prevented 55 from turning while the sleeves as 72 and 73 abut against the insides of the uprights and serve to space them apart. The nuts are upon the outside of the walls as shown and, when tightened, securely bind the corner 60 structure in place. At the edges of the uprights as described, and extending beyond the same, are cleats 75, 76, 77 and 78 against which the sections as 79, 80, 81 and 82 of the retaining walls are laid and these sections are spaced apart by anchors as 83 and

84 which are precisely like the anchors 27 of Figs. 1 and 2, the laying up of the sections, their securing and removal being accomplished in precisely the same manner as described in connection with Figs. 1 and 2. 70

The modified corner centering which is shown in Fig. 11 comprises inside corner post 90 against which are laid the sections as 93 and 94 for forming inside retaining walls. These sections may be secured against 75 the cleats 91 and 92 by means of an anchor 95 which is precisely like the anchor 27 of Figs. 1 and 2. In this construction of corner an outside corner upright is dispensed with, the outside retaining sections as 96 80 and 97 being properly spaced and secured by means of anchors as 98 and 99 which are precisely like the anchors 27 of Figs. 1 and 2. As shown, the sections of one outside retaining wall overlap the ends of sections forming 85 an outside retaining wall running at an angle thereto, the overlapping sections carrying a cleat 100 which serves to guide the ends of the abutting planks of the adjacent outside wall. The joint at the corner 90 may be rendered secure by means of anchor as 101 which is precisely like the anchors 98 and 99. In the construction just referred to, the planks are laid up and removed in a manner analogous to that described in connection with Figs. 1 and 2. The corner mold last referred to may be used with advantage where the absolutely true and smooth formation of the corner is not of importance and a rougher finish is satisfactory. 100

While the invention has been illustrated, in accordance with the patent statutes, by what is considered its best application, it may have other embodiments, without departing from its spirit, and should not therefore be limited to the structure shown. 105

What I claim is—

1. In a mold for plastic material, the combination with a skeleton frame comprising pier and girder boxes opening into each other, of plates, forming a retaining wall for one side of the plastic material, laid against said frame, and a retaining wall for the other side of the plastic material. 110

2. In a mold for plastic material, the combination with a skeleton frame comprising pier boxes, of plates, forming a retaining wall for one side of the plastic material, laid against said frame, and a retaining wall for the other side of said plastic material. 115

3. In a mold for plastic material, the combination with a skeleton frame comprising girder boxes, of plates, forming a retaining wall for one side of the plastic material, laid against said frame, and a retaining wall for the other side of said plastic material, said girder boxes opening into the space between the retainer walls. 120

4. In a mold for plastic material, the combination with plates forming a retaining 125

6 wall for one side of the plastic material, uprights against which said sections are laid and which serve as guides therefor, a retaining wall for the other side of the plastic material, and means for supporting said plates, each of said means extending from between two adjacent plates and comprising a driven fastening securing said means to the plate upon one side of it, said means being uncured to the plate upon the other side of it and said means extending into the space between the retaining walls.

5. In a mold for plastic material, the combination with plates forming a retaining wall for one side of the plastic material, uprights against which said plates are laid and which serve as guides therefor, a retaining wall for the other side of the plastic material, and means for supporting said plates, each of said means extending from between two adjacent plates and comprising a driven fastening securing said means to the section upon one side of it, said means being uncured to the section upon the other side of it, and said means extending through the space between the retaining walls and engaging with the other wall.

6. In a mold for plastic material, the combination with an upright, of retaining walls for the plastic material comprising separately removable plates laid against said upright and forming the inner retaining walls for the plastic material at a corner of the structure, the said retaining walls being at an angle with each other, a second upright and separately removable plates forming the outer retaining walls at the said corner laid against said second upright, the walls formed by the plates against said second upright being at an angle, and the plates forming one of the outer retaining walls overlapping said second upright, the plates forming the other of said outer retaining walls abutting against said second upright.

7. In a mold for plastic material, the combination with a plurality of plates forming

a retaining wall upon one side, a retaining wall upon the other side, and means for supporting said plates extending from between adjacent plates into the space for the plastic material between said walls, each of said means engaging with a plate upon one side only to prevent its sidewise movement, the plate upon the other side of said means being unrestrained in its sidewise movement.

8. In a mold for plastic material, the combination with a retaining wall comprising plates, of a second retaining wall comprising plates, and rods extending from between adjacent plates of one wall through the space for the plastic material between said walls and between adjacent plates of the other wall, each of said rods engaging with the plate upon one side of it to prevent its sidewise movement, the adjacent plate upon the other side of the rod being unrestrained by said rod in its sidewise movement.

9. In a mold for plastic material, the combination with a retaining wall comprising plates, of a second retaining wall comprising plates, rods extending through the space for the plastic material between the walls and engaging with said walls, each of said rods having its end bent at an angle upon the same side of the axis of the rod and in the same plane, said bent ends forming driven fastenings, each of said rods extending between two adjacent plates of one wall and having one of its bent ends driven into the edge of one of said plates, its other end entering between adjacent sections of the other retaining wall and its other bent end being driven into the edge of one of the sections thereof.

In testimony whereof I hereunto set my hand, in presence of two witnesses, this 31 day of December, 1907.

ARTHUR I. ENGLISH.
